N. Y., A CORPORATION OF NEW YORK.

TRACKER MECHANISM.

No. 902,479.

Specification of Letters Patent.

Patented Oct. 27, 1908.

Application filed July 14, 1906, Serial No. 326,161. Renewed August 24, 1908. Serial No. 450,055.

To all whom it may concern:

Be it known that I, THOMAS DANQUARD, a citizen of the United States, residing at New York, in the county of New York and State 5 of New York, have invented a new and useful Tracker Mechanism, of which the following is a specification.

In mechanical musical instruments and playing attachments for musical instruments, 10 it has been the ordinary practice to provide a tracker-bar with 65 channels corresponding to only 65 of the 88 keys of an ordinary piano. This obviously limits the range of such mechanical pianos and players and consequently 15 instruments have been built with a tracker-bar provided with 88 channels, from which all the notes of the piano can be played. Obviously this necessitates the use of two kinds of music sheets, the great bulk of sheets 20 already existing being made to use with tracker-bars having 65 channels.

The principal objects of the present invention are to provide for using both kinds of sheets on the same piano without resorting 25 to complicated and expensive mechanism for that purpose. This I accomplish by providing two tracker-bars preferably stationary and connecting the channels to a single set of primary pneumatics sufficient in number 30 to accommodate the 88 channels of one tracker-bar and by providing a cap plate adapted to close either set of channels and leave the other set in proper position for receiving the perforated paper and operating 35 in the usual way.

Further objects and advantages of the invention will appear below.

Reference is to be had to the accompanying drawings in which,

40 Figure 1 is a plan of one end of an instrument constructed in accordance with the principles of my invention. Fig. 2 is a transverse sectional view of the same, and Fig. 3 is a fragmentary view similar to Fig. 2 showing 45 the parts in a different position.

The tracker-bar is usually placed between two rolls 10 and 11 for receiving and taking up the music sheet. In a similar position but further away from the rolls so as to 50 cause the paper to come away from the rolls at a greater angle to the line joining their centers, I locate a pair of tracker-bars 12 and 13. Each of these bars is provided with the usual channels 14 and one bar 12 is made in 55 the form ordinarily employed in the majority

of instruments at the present time, preferably with 65 channels spaced in the ordinary way. The other bar 13 is provided with a larger number of channels, preferably 88 so that all of the keys can be manipulated from it. 60

The two tracker-bars are fixed at a slight distance from each other and the lead tube connections are also stationary. Each of the tubes from the tracker-bar 13 which has the largest number, is connected with a primary pneumatic 15 through a suitable connection 16. Each of the tubes connected with the channels of the bar 12 is led into a passage with which one of the tubes from the other tracker-bar is connected so that the 70 number of pneumatics and connections 15 does not have to be increased beyond the number required for a tracker-bar having the larger number of channels.

The operating mechanism controlled by 75 the pneumatic 15 may be of any desired kind or character and does not constitute a part of the present invention.

From the description above given, it will be seen that each tracker-bar is to be used 80 with one kind of music sheet, and that the tracker-bar which is not to be used at any time must be closed so that the channels will not conduct air to the pneumatics and the other tracker-bar left open so that it can be 85 used in the ordinary manner. It is for the purpose of accomplishing this result that the tracker-bars are placed farther from the centers of the rolls than has heretofore been the case and for the same purpose they are given 90 a greater angle on their upper surfaces; that is, each of the tracker-bars is slanted considerably so that the paper coming from or passing to the inner roll will pass over the surface and at all times cover the channels 95 therein so that the perforations in the paper can be depended on in the usual way to control the action.

For the purpose of simultaneously opening one set of channels and covering the other, a 100 cap plate 17 is provided. This cap plate may be made of brass or any other suitable metal or material and is given such shape on the bottom that it will accurately cover the openings in either of the tracker-bars. It is 105 desired to move the cap plate back and forth as conditions require, to accomplish the desired result. For the purpose of conveniently holding the cap plate in position and shifting it from one tracker-bar to the other, 110

I have shown it as mounted upon a pair of pivoted arms 18. Each of these arms has a screw projection 19 extending above the cap plate and a knob 20 which screws into this 5 projection and removably holds the cap plate in position on the arms 18. The arms project through slots 21 in the two tracker-bars and it will be seen that a most convenient means is thus provided for quickly and efficiently 10 opening the channels of one tracker-bar for operation and closing those of the other. The ends of the slots 21 limit the motion of the arms 18.

In operation, the paper passes over one 15 tracker-bar at such an angle that the channels are normally closed by the paper except where perforated and then over the cap plate which covers the other tracker-bar. From a comparison of Figs. 2 and 3, it will be seen 20 that the paper will pass over the proper tracker-bar at the desired angle in both positions of the cap plate, and that the idler rollers, which are often employed at the sides of the tracker-bar can be dispensed with.

25 For the purpose of resiliently forcing the cap plate on the tracker-bars springs 23 are provided, these springs being connected with the cap plate at one end and at the other with a block 22 which supports the tracker-bars 30 and the arms 18. Owing to the slant of the top of the tracker-bars the tension of the springs may increase as the cap plate is moved outwardly; thus making the cap plate fit more tightly on the tracker-bar. It will 35 be seen that from this construction, the tracker-bars and cap plate will guide the paper so that without idler rollers the music sheet will always be in proper position on one tracker-bar while the other is closed.

40 As the music sheet passes over the cap plate on the closed tracker-bar, it will be seen that the angle of the tops of the tracker-bars and the thickness of the cap plate will be such that the cap plate will not lift the paper 45 from the tracker-bar so as to expose the channels. Thus by a most simple and easily operated construction, the advantages of both kinds of tracker-bars are secured and all the music sheets which are ordinarily employed 50 on both kinds of instruments can be used on a single one without excessive manipulations of the parts and without taking away or replacing any of them.

55 While I have illustrated and described a particular form in which my invention may be embodied, I am aware that many modifications may be made therein without departing from the scope of my invention as expressed in the claims. Therefore, I do not 60 wish to be limited to the exact construction shown, but

What I do claim and desire to secure by Letters-Patent is:—

1. The combination of a pair of stationary tracker-bars, and means for simultaneously closing the channels of one bar and opening those of the other.

2. In a mechanical musical instrument, the combination of a pair of stationary tracker-bars, each having channels, and a cap plate for closing the channels of one bar and simultaneously opening those of the other.

3. The combination of a plurality of stationary tracker-bars, and a movable cap plate adapted to close the channels in all of the bars alternately.

4. The combination of two stationary tracker-bars, and a cap plate pivoted to swing between said bars and to alternately close the channels thereof.

5. The combination of two tracker-bars, a cap plate pivoted to swing between said bars and to alternately close the channels thereof, and means for yieldingly forcing the cap plate against the surfaces of the bars.

6. The combination of two tracker-bars, a movable cap plate adapted to close the channels in either bar, and a spring for yieldingly forcing the cap plate against the surfaces of the bars.

7. The combination of a pair of tracker-bars, a block upon which said bars are mounted, a pair of arms pivoted to said block at a point between the tracker-bars and below them, a cap plate mounted on said arms, and means for movably securing the cap plate to the arms.

8. The combination of a pair of tracker-bars having operating surfaces slanted in opposite directions, a pair of arms pivotally mounted adjacent to said tracker-bars and between them, a cap plate mounted on said arms, and a pair of removable knobs for securing the cap plate to the arms and for manipulating the cap plate.

9. The combination of a pair of paper carrying rolls, a pair of tracker-bars located between the rolls, said tracker-bars having surfaces slanting oppositely toward the rolls and located out of the direct path of the paper between the rolls, and a cap plate adapted to cover either of said tracker-bars and to guide the paper between one roll and the opposite tracker-bar.

In testimony whereof I have hereunto set my hand, in the presence of two subscribing witnesses.

THOMAS DANQUARD.
